UNITED STATES PATENT OFFICE.

ROBERT J. SHEEHY, OF NEW YORK, N. Y., ASSIGNOR, BY MESNE ASSIGNMENTS, TO WENDELL GOODWIN, OF SAME PLACE.

PRINTING-TELEGRAPH EXCHANGE SYSTEM.

SPECIFICATION forming part of Letters Patent No. 506,272, dated October 10, 1893.

Application filed December 31, 1887. Renewed March 15, 1893. Serial No. 466,172. (No model.)

To all whom it may concern:

Be it known that I, ROBERT J. SHEEHY, a citizen of the United States, residing in New York, in the county and State of New York, have invented certain new and useful Improvements in Printing-Telegraph Exchange Systems, (Case E,) of which the following is a specification.

The invention relates to an organization of circuits and apparatus for telegraphic inter-communication and other similar purposes.

The general purpose of the invention is to provide means whereby telegraphic apparatus located at different stations may be electrically connected with each other through a central station and supplied with the necessary currents for operation over a single main line conductor.

The invention consists in locating at a central point, suitable sources of alternating electric impulses such as an alternating current dynamo which may be connected with any pair of main line conductors, so that any two such conductors may be connected together and supplied with the requisite currents for operation; and the instruments themselves are organized in such a manner that they may be operated by currents transmitted over the line connected therewith and upon a cessation of such currents effect impressions.

In the accompanying drawings, Figure 1 is a diagram showing the general organization of apparatus and circuits for carrying out the invention. Fig. 2 is a detail of one of the instruments.

Referring to the figures, A represents a dynamo that generates alternating electric impulses. This is here provided with an armature wound with several sets of convolutions, as shown at b', b², b³. The armature-shaft carries pairs of contact rings a', a², a³, a⁴, a⁵ and a⁶. These pairs are connected respectively with the terminals of different bobbins or armature-coil sections so that each pair delivers to its brushes c', c², c³, c⁴, c⁵, c⁶, alternating electric impulses, independently of the others. The brushes c', c², c³, &c., are connected with contact-plates d', d², d³, d⁴, d⁵ and d⁶, respectively of a switch-board D, by means

of conductors 1, 2, 3, 4, 5, and 6. Electric indicators e', e² and e⁵ may be included in the conductors 1, 3 and 5, respectively, for the purpose of showing whether or not currents are at any time traversing such conductors. The plates d', d², d³, &c., may be placed in electrical connection, by any suitable form of switch-plugs, with any of a series of plates f, f', f², f³, f⁴. The plate f is connected, by a conductor 1, with an instrument M at the central station which will be hereinafter described. The plates f', f², f³, f⁴, are respectively connected by the conductors 11, 12, 13 and 14 with switch points g', g², g³ and g⁴, of indicating devices G', G², G³ and G⁴.

At different points there are located telegraphic instruments M', M², M³ and M⁴ similar to the instrument M, and they are connected by conductors L', L², L³ and L⁴, with the switches h', h², h³ and h⁴ of the indicating devices G', G², G³ and G⁴. Normally the switches rest upon points electrically connected through suitable signaling devices I', I², I³ and I⁴, and by means of a conductor 7, with the earth at G. When a subscriber at M' for instance, desires to be connected with another subscriber of the system, a current is sent over the line L' and thus through the instrument I' to the earth. The operator at the central station thereupon moves the switch h' to the point g', thereby connecting the line L' through the line 11 to the switch plate f'. This plate may then be connected with a plate d' and thus through the brush c' and the corresponding section of the armature to the brush c², thence by the way of the conductor 2 to the plate d². This plate may be connected with the plate f and thence through the line 1 with the instrument M and through this instrument, by a conductor 9 with the earth at E. The instrument at M' is also connected with the earth at E so that the two instruments are connected in series. After the operator has ascertained that the subscriber at M' desires to be connected with a subscriber at M⁴, for instance, it is necessary only to place the plate d³ in connection with the plate f⁴, instead of with the plate f, and move the switch h⁴ to the point g⁴, when the two instruments M' and M⁴ will be connected with each other through the brushes 100

c' and *c*², and either instrument may be operated by the other. If at any time it is desired to place the instrument M in circuit also, this may be done by means of a split 5 switch-plug in a manner well understood. The indicators *e'*, *e*³ and *e*⁵, will show whether any given bobbin section is being used at any time, and thus show whether the connected subscribers have finished using the line.

10 In case two instruments located at very distant points are to be connected with each other, it may be desired to employ currents of greater strength than are delivered from one section of the armature bobbins. In such 15 case two or more sections may be connected in series. Thus the brushes *c*² and *c*³ might be connected through the switch-board or otherwise, and the connections continued from the brush *c*⁴ in the same manner as formerly 20 continued from the brush *c*². The sections may be connected in multiple for quantity currents.

The construction of the instruments at M, M', M², &c., which it is preferred to employ, is as follows:—Referring to Fig. 2, the line L' enters at a binding post *n'*, thence it passes by way of a conductor 10 to a switch key P. This key normally rests against a contact-point *p*. A conductor 11 connects 25 this point with a lever *r* applied to an electro-magnet R. This lever normally rests against a point *r'* which is connected by a conductor 12, to the coils of an electro-magnet T. From this magnet the connections are continued, 30 by a conductor 13, to a binding-post *n*² and thence by the conductor 14 to the earth at E'. The electro-magnet T is employed for operating an escapement-lever *u* applied to a scape-wheel *u'* upon the shaft *u*² carrying the type-wheel U. The escapement lever *u* is carried 35 upon a movable section or armature *t* of the electro-magnet. This extends loosely within one end of the hollow core *t'*, to which it is pivoted. The armature *t* passes between the 40 poles N and S of a permanent or polarized magnet V'. If, therefore, alternating electric impulses traverse the coils of the magnet T the escapement-anchor will be vibrated and thus govern the movements of the type-wheel.

Impressions are effected from the type-wheel by means of a lever *q* of an electro-magnet Q; this electro-magnet is included in the circuit of a local battery o. One pole of 55 this battery being connected with the binding post *n*⁴, and by a conductor 15 through the coils of the magnet Q to a contact point *q*'. A lever Q' carrying an armature *q*², which may surround the core-armature *t* and is applied to the pole of the hollow core *t'*, carries 60 an insulated contact *q*³ which normally rests against the point *q*', by reason of the spring *s*. A conductor 16 connects this contact with a contact-spring *q*⁴, which when released rests against a corresponding point *q*⁵. The point *q*⁵ is connected by a conductor 17 with the binding-post *n*³ and thence with the

remaining pole of the battery o. If, therefore, the points *q*⁴ and *q*⁵ are in contact, the magnet Q will be vitalized each time the point *q*³ is allowed to rest against the point *q*'. As long as alternating electric impulses continue to traverse the coils of the magnet T, however, the armature is held down and the circuit is interrupted, but upon the cessation of such impulses the circuit will be closed at the points *q*' and *q*³, and the magnet Q will thus be vitalized and an impression effected from the type-wheel. 75

In order to prevent the waste of the battery o, when the instrument is not in use, a device is employed for separating the points *q*⁴ and *q*⁵. This consists of a latch *q*⁶ which may be caused to engage an arm *q*⁷ upon the lever Q', and to press the spring *q*⁴ back, but the moment the lever Q' is drawn downward, this latch is released and allows the points to come together, and it is only replaced by hand. 80

When it is desired to send a signal from this instrument to the central station, the switch key P is employed. By pressing this down, a contact *p*³ strikes two contacts *p*¹ and *p*². The former of these is connected by a conductor 18 with a binding-post *n*⁵ and thus by a conductor 19 with one pole of a battery o'. The other pole of this battery is connected by a conductor 20 with a binding-post *n*⁶, and by a conductor 21 with the binding-post *n'* and thus with the line L'. The point *p*² is connected by a conductor 22 with the binding-post *n*³ connected with one pole of the battery o; the other pole of this battery being connected through the binding-post *n*⁴ with the conductor 15. But the conductor 15 is also connected by a conductor 24 with the binding-post *n*² and thus with the earth at E. The closing of the key P therefore serves to connect the batteries o and o' in series with their poles in the proper relation to transmit a current upon the line L'. This current will 90 operate the indicating device I' for instance, at the central station. 95

When it is desired to transmit from the instrument a key-board V is employed. This consists of keys *v* electrically connected with the separate plates *w* of a sunflower W. The contact arm *w*' of the sunflower is carried upon the shaft *u*² of the type-wheel, and is electrically connected through the coils of the magnet R with the binding-post *n*⁶, and thus with one pole of the battery o'. The other pole of this battery is connected through the binding-post *n*⁵ with the contact plate for all the keys *v* by means of a conductor 23. When therefore, any key is depressed and the contact arm *w*' strikes the corresponding segment of the sunflower W, the circuit of the battery o' will be closed through the magnet R. This will momentarily interrupt the circuit connections of the line L', since it will draw the armature lever *r* away from the point *r'* and therefore the armature lever *t* of the magnet T will remain in whatever position it chances to be at the moment, and a 100 105 110 115 120 125 130 135

corresponding impression will be effected from the type-wheel of the instrument, and also from the type-wheel of any corresponding instrument connected therewith through 5 the source of alternating electric impulses at the central station. Upon releasing the key the magnet R will be demagnetized and the connections of the line L' again completed.

In case it is not desired to interrupt the 10 main line connections, the magnet T may be shunted by the contact of the lever r with a front contact-point r^2 which is connected by the dotted conductor with the conductor 13.

I claim as my invention—

15 1. The combination of a series of printing telegraphic instruments, located at different points, a main line for each instrument running to a central station, two or more sources of continuous or regular electric impulses, 20 located at the central station, for actuating said printers step by step, and means for connecting any two of said main lines through any of the sources of electric impulses, substantially as described.

25 2. The combination of telegraphic instruments operated by alternating currents located at different points, conductors leading therefrom to a central station, switch connections at the central station whereby any of 30 the conductors may be connected with each other, two or more sources of alternating electric impulses and circuit-connections whereby any one of said sources may be connected in the circuit of any two of said main lines.

35 3. In a telegraphic system, the combination of a series of telegraphic instruments located at different points, main line conductors leading therefrom to a central station, a generator of alternating electric impulses at the central station having independent circuit connections from its armature sections whereby independent electric currents may be derived therefrom, and a switch-board or equivalent device whereby any two of said lines may be 40 connected with each other through any of said armature sections.

4. In a telegraphic instrument, an electromagnet having a hollow core, a soft iron bar extending into said core, and movable thereon, 50 a permanent magnet applied to the soft iron bar, and a supplemental armature applied to the hollow core.

5. The combination of a type-wheel, an escapement device therefor, a press lever for effecting impressions from the type-wheel, a magnet for operating the press lever, a magnet and armature for vibrating the escapement device, and a supplementary armature applied to the escapement magnet and attracted thereby while the escapement device 55 is vibrated, and contacts and circuit-connection whereby the first-named magnet is energized when the supplementary armature moves away from its magnet.

65 6. The combination in a telegraphic instru-

ment of a press magnet, a circuit therefor, an escapement magnet, its armature electrically actuated in both directions to operate the escapement pallet, and a supplementary armature applied thereto controlling the circuit connections of the press magnet, the supplementary armature being attracted while the escapement pallet is being vibrated.

7. The combination, in a telegraphic instrument, of a recording magnet, a circuit therefor, an escapement magnet, an armature applied thereto controlling the circuit-connections of the recording magnet, and a mechanical circuit-interrupting device for the recording magnet released upon the movement of the 75 armature applied to the escapement magnet.

8. The combination of a type-wheel, its escapement device, a polarized magnet consisting of a coil and hollow iron core, a polarized iron bar or armature arranged within the hollow core and actuating the escapement lever or pallet, the press lever and its magnet, and a supplementary armature applied to the polarized escapement magnet and controlling the circuit of the press magnet, substantially 85 as set forth.

9. In a telegraphic instrument, a signal transmitter consisting of a movable key, a battery, contact-points for the key connecting one pole of the battery with the main line 95 and the other pole with the earth upon the operation of the key, and a second battery connected in series therewith upon the operation of the key, said second battery having local connections through the press magnet 100 of the instrument, substantially as described.

10. The combination with a telegraphic instrument, of a local battery and connections therefrom through the transmitting device of the instrument, a second battery and local 105 connections therefrom through the printing magnet of the instrument, a circuit-controlling or signaling key, and contact points therefor whereby said batteries are coupled in series upon the operation of the key, and connections from the key with the main lines substantially as described.

11. The combination of the main line conductors, telegraphic printing apparatus connected therein and adapted to be operated 115 by an alternating current, an alternating current electric generator having two or more bobbins sections, independent collectors for said sections, and circuit controllers adapted to connect any two printers of the system 120 through one or more of said sections, substantially as set forth.

In testimony whereof I have hereunto subscribed my name this 30th day of December, A. D. 1887.

ROBERT J. SHEEHY.
